UNITED STATES PATENT OFFICE.

JOHN F. MILLER, OF PITTSBURG, PENNSYLVANIA, ASSIGNOR TO DANIEL RISHER, OF SAME PLACE.

SPRING DRAFT OR TUG LINK.

SPECIFICATION forming part of Letters Patent No. 224,210, dated February 3, 1880.

Application filed December 19, 1879.

To all whom it may concern:

Be it known that I, JOHN F. MILLER, of Pittsburgh, county of Allegheny, State of Pennsylvania, have invented or discovered a new and useful Improvement in Spring Draft or Tug Links; and I do hereby declare the following to be a full, clear, concise, and exact description thereof, reference being had to the accompanying drawings, making a part of this specification, in which—like letters indicating like parts—

Figure 1 illustrates, by a sectional elevation, my improved spring draft or tug link. Fig. 2 shows a transverse section of the same, taken in the line $x x$, Fig. 1. Fig. 3 also shows a transverse section, but taken in the line $y y$, Fig. 1; and Fig. 4 is a perspective view of one part or member of the body of the link.

My present invention relates to spring draft or tug links, and more particularly to the construction and arrangement of the U-shaped bars which form the body or barrel of the link. It is constructed as follows: Four segmental bars, A A and B B, are arranged in such way that their rounded or convex outer faces form a barrel or cylinder, as seen in Fig. 1. The two opposite bars A A are connected at one end by a loop, A', of any desired form and size, except as hereinafter provided, and the opposite ends of bars B B are connected by a similar loop, B'. The external width of this loop B' should not be greater than the diameter of the barrel A B, for reasons which will presently appear.

Upset heads or collars a and b are made on the open ends of the bars A and B, which serve as shoulders or bearings for a coiled spring, C, which encircles the barrel A B.

The inner faces of the bars A and B are made flat, with the two opposite faces arranged parallel. The edges of these bars next to their respective connected ends are cut away, as at c , leaving the bars along such cut-away parts equal in width to the distance between the flat inner faces of the two adjacent bars, while full edges c' are left on the bars next to their open or unconnected ends, the length of which full edges is, by preference, equal to half the length of spring C when compressed to the full extent desired. In putting

these parts together the spring C is first placed on the U-shaped bars A A, Fig. 4, by compressing their open end. Then, by making the loop A' equal in thickness to the distance between the inner faces of B B, it may be passed between them into the loop B'. These bars B B are then pushed, the loop B' being foremost, between the bars A A until the shoulders a and b bear against the ends of spring C and the two loops A' and B' project from the opposite ends of the device, as in Fig. 1.

As thus arranged, each of the four segmental bars—as, for example, the front bar, B, Fig. 1—will have two different kinds of bearings against or upon its two adjacent bars, as A A—that is, along the narrow cut-away part c it will have edge-bearings against the flat inner faces of A A at c' , as shown in Fig. 2, while along the full part of B it will have a reverse relation, as in Fig. 3—that is, a face-bearing against the edges of A A. I thus secure two edge and two face bearings for all and each of the bars. Such an arrangement greatly increases the strength and durability of the device, and prevents all possibility of the bearing-edges of the bars from becoming relatively displaced, as has been found to be the case where the bars have either a miter-edge bearing along their entire length, or, on the other hand, where they have face-bearings only.

By properly arranging the relative lengths of cut-away and full edges c and c' , I secure a distance between shoulders e and e' , made by cutting away the edges c , as described, equal to the desired range of action of the spring; then, as the bars A and B have movement upon each other, caused by strain upon the two ends, the shoulders e and e' come against each other, and thus prevent further compression of the spring. I thus prevent danger of breaking or injuring the spring by too great compression, which is an important consideration in spring draft-links. As before described, I prefer to secure this distance between stops e and e' , or the desired range of spring action, by making the several edges c' equal in length to half the length of the compressed spring; but this preference is based

principally on convenience in construction, as the acting distance between stops *e* and *e'* may be secured by making some of the edges *c'* shorter than mentioned, and others, which act 5 with or against them, proportionately longer.

By the construction described I secure a spring draft or tug link superior both in durability and simplicity.

It will be observed that the maximum strain 10 on the shoulders *a* and *b* is in all cases measured by the carrying-power or elasticity of the spring, and that any excess of strain is borne by the stops *e* and *e'*. Danger of breaking the shoulders *a* and *b* is thus obviated.

15 I claim herein as my invention—

1. In a spring draft or tug link, the combination of the U-shaped segmental bars A and B, such bars having cut-away edges *c* through

a part only of their length, and being arranged substantially as described, whereby each of 20 the bars has both edge and face bearings upon and with its two adjacent bars.

2. The combination of spring C, U-shaped bars A and B, shoulders *a* and *b* on the open ends of the bars, and stops *e e'*, made by cutting away the edges of the bars through a part 25 of their length, such stops being arranged and adapted to limit the compression of the spring, substantially as set forth.

In testimony whereof I have hereunto set 30 my hand.

JOHN F. MILLER.
